HARRY M. BROWN, OF BROOKLYN, NEW YORK, ASSIGNOR TO SPRING STOPPER COMPANY, OF BROOKLYN, NEW YORK, A CORPORATION OF DELAWARE.

MACHINE AND METHOD FOR MAKING CARBOYS OR LARGE GLASS CONTAINERS.

1,334,648.

Specification of Letters Patent. Patented Mar. 23, 1920.

Application filed February 28, 1919. Serial No. 279,809.

To all whom it may concern:

Be it known that I, HARRY M. BROWN, a citizen of the United States, residing at 217 Duffield street, Brooklyn, in the county 5 of Kings and State of New York, have invented a new and useful Improvement in Machines and Methods for Making Carboys or Large Glass Containers, of which the following is a specification.

10 This invention relates particularly to the manufacture of carboys or other large glass containers, and to a machine adapted to such manufacture; and the primary object is to provide an improved method of manufacture and a machine adapted to such manufacture which is simple in construction, easy of operation, and of large output capacity, adapted for the commercial production of carboys, or other large containers, 15 provided with internally-threaded mouth-portions adapted to receive threaded stoppers.

20 A further object is to provide a simple machine of the character indicated, which is labor-saving in operation.

The invention is illustrated, in a preferred simple embodiment, in the accompanying drawings, in which—

Figure 1 represents a broken vertical section 30 tional view of the improved machine, or press, the section being taken approximately as indicated at line 1 of Fig. 2, and the dotted lines indicating the bodily shifted position of the plunger of the mold 35 and its actuating mechanism; Fig. 2, a plan sectional view taken approximately as indicated at line 2 of Fig. 1, one of the mold locks mounted on the carriage being indicated by dotted lines, however; Fig. 3, a 40 broken rear elevational view of the machine; Fig. 4, a vertical sectional view taken approximately as indicated at line 4 of Fig. 1; Fig. 5, a broken sectional view of the mouth of the carboy or container, the section being taken as indicated at line 5 of Fig. 6; Fig. 6, a broken axial sectional view of the mouth-portion of the container; Fig. 7, an enlarged broken central vertical 45 sectional view, showing the mandrel and its actuating mechanism; Fig. 8, an end view of the mandrel and an elevational view, partly sectional, of the air-cooling means for the mandrel; Fig. 9, a broken side elevational view of the mandrel; and Fig. 10, 50

a broken front perspective view of the 55 plunger which serves to press the glass into the mold in the operation of forming the head of the carboy, said plunger itself serving as a section of the mold when completely depressed.

60 In the embodiment illustrated, A represents the bed, or base-plate, of the machine, mounted on legs A'; B, a three part neck-mold mounted on the bed A and adapted to be opened and closed by means of foot- 65 actuated mechanism B'; C, an arbor having one end projecting into the mold, said arbor being equipped with collapsible means for forming thread-segments in the interior of the bottle-mouth, the mandrel being projected into the mold and retracted, as desired, by mechanism C'; D, mechanism for forcing molten metal into the mold, said mechanism being mounted on a carriage D' which is shiftable on the bed-plate A by 70 means of mechanism D²; and E, a mandrel cooling device mounted on the bed-plate A. The carriage D' has its uprights equipped with elongated mold-locking cams D³ (one shown in full lines and one in 75 dotted lines in Fig. 2), which serve to lock the closed mold, both when the mechanism D is in the full line position and in the dotted line position shown in Fig. 1. When, 80 however, the carriage D' is wholly retracted, the mold can be opened to permit removal of the carboy. The mold is held locked by the members D³ while the mechanism D is in the dotted line position shown in Fig. 1 during the introduction of the 85 metal (plastic glass) into the charging chamber which forms an upward extension of the mold; and the members D³ also lock the mold when the mechanism D is in position for performing the pressing operation. 90 Because of the desirability of preventing the mold-sections from springing apart during the application of heavy pressure, however, it is preferred to equip the plunger of the mechanism D with a loosely mounted 95 locking cap D⁴, which drops into locking position when the plunger begins to descend.

100 The frame of the machine may be of any suitable construction. Preferably it comprises the bed plate A supported as shown; and the construction of the machine is such as to permit a carboy F to be disposed hori-

zontally in front of the machine, with the neck of the carboy projecting into the mold B.

The carboy is usually blown in an iron mold, in which it is formed with a neck-portion 1, which requires to be reinforced and provided with an internal thread, or with internal thread-segments, which operation is performed in the machine herein described. While the carboy, or the neck-portion thereof, is hot, it is entered in the mold B; and a gob of hot or molten glass is introduced and pressed into the mold, the mandrel being in the position shown in Fig. 1. In this operation, the head and mouth-portion of the carboy is formed and becomes practically integral with the neck of the carboy, and the mouth-portion is provided with internal thread-segments. The mandrel is then withdrawn, the levers or thread-equipped segments of the mandrel being first collapsed, and the carriage D' is wholly retracted, which enables the mold to be opened, thus permitting the carboy to be lifted out of the mold. The carboy is then placed in an annealing furnace where it remains until properly tempered.

The mold B comprises a lower half-section 2, which is firmly secured upon the bed-plate A by any suitable means (not shown); and a pair of upper quarter-sections 3 equipped with arms 3^a which are connected by horizontal pivots 4 with pivot-lugs 5, which project laterally from the lower mold-section 2. The upper mold-sections 3 are provided with upward extensions 3^b, which together form an upward extension of the mold and afford a cavity for receiving the charge of molten metal, or plastic glass, which is to be pressed into the mold to form the carboy-head. This cavity preferably is of rectangular cross-section and through it is adapted to work snugly the plunger, which is of corresponding cross-section and whose lower end forms a portion of the wall of the mold-cavity when the plunger is completely depressed. The upward extensions 3^b have their outer sides equipped with lock-engaging lugs 3^c, adapted to be engaged by the mold-locking cams D³.

The neck-mold B is adapted to be opened and closed by means of the mechanism B', comprising a vertical plunger 6, working through the bed-plate A and equipped at its upper end with a cross-head 6^a; a pair of links 6^b connecting said cross-head with the arms 3^a of the quarter-sections 3 of the mold; and a foot-lever 6^c whose inner end is connected, by a link 6^d, to the lower end of the plunger 6. Assuming the mold to be unlocked, depression of the outer end of the foot-lever 6^c will elevate the plunger 6 and throw the quarter-sections 3 of the mold to the open position. Reverse movement of the foot-lever, as by means of a

weight 6^e, will close the mold; or the weight of the mold-sections 3 and the plunger may be depended upon to close the mold, when the pressure upon the foot-lever is removed.

The mandrel C is adapted to be projected and retracted by a cross-head 7 carried by a pair of plungers, or stems, 7^a (Fig. 2), said plungers 7^a extending through stuffing boxes 7^b into cylinders 8, and being equipped within the cylinders with pistons 7^c, in the usual manner, as indicated by dotted lines in Fig. 7. The pistons are preferably actuated forwardly and backwardly by compressed air, the admission and exhaust being controlled by a valve 9 which is equipped with a handle, or controlling lever, 9^a, located within convenient reach of an operator standing in position to operate the foot-lever 6^c.

The mandrel C extends freely through a perforation with which the cross-head 7 is provided at a central point. The rear portion of the mandrel extends through a guide 10, which is provided in a wall formed integrally with and interposed between the cylinders 8. Fig. 7 shows the mandrel in its completely projected position, in which position a shoulder, or nut, 11, on the rear end of the mandrel engages the rear wall of the guide. The front end of the mandrel is equipped with a tip 12 which is adapted to extend into the mold-cavity, so that the end-portion of the carboy-neck will embrace the mandrel. The tip 12 is provided at its base with an enlarged portion 12^a which has slots, or recesses, 13, which accommodate a pair of oppositely disposed levers 14, carried by pivots 15. The front end-portions 14^a of the levers 14 are shaped to conform to the reduced tip-portion 12 of the mandrel, of which they, in effect, form collapsible sections. The tip-portions 14^a of the levers are provided with thread-segments 14^b, formed by making suitable counter-sinks in the tip-portions, so that when the molding operation is performed the inner wall of the carboy-mouth will be provided, as shown in Figs. 5 and 6, with projecting, or raised, thread-segments 15^b, separated by segmental spaces 15^a. Thus the carboy will be adapted to receive a glass stopper equipped with corresponding thread-segments which can be entered through the spaces 15^a, after which the stopper can be rotated into interlocking engagement with the thread-segments 15^b. Thus, the stopper is introduced by a longitudinal movement and secured by a partial rotation in a manner similar to that in which the breech-block of a large gun is introduced and secured in place.

The mandrel C, which, as stated, extends freely through a perforation in the cross-head 7 is equipped with a lever-actuating block, or sleeve, 16, which is slidably mount-

ed on the mandrel. The mandrel is tubular, as shown in Fig. 7; and within the mandrel is a tension spring 17 whose rear end is connected, by a pin 18, with the rear end of the mandrel, and whose front end is connected, by a pin 19, with the lever-actuating member 16. That is, the ends of the pin 19 are fitted into perforations in the sleeve 16, and the pin 19 works freely in a slot 20 with which the tubular mandrel is provided. In the projection of the mandrel, the cross-head 7 bears against the rear end of the lever-actuating member 16; and when the cross-head is projected, it moves the member 16 toward the mold, and the tension of the spring 17 is sufficient to cause the mandrel to move with the member 16. When, however, the stop 11 on the rear end of the mandrel engages the rear end of its guide, the mandrel can move no farther and the continued movement of the cross-head slides the member 16 on the mandrel and actuates the levers 14 in such manner as to separate the threaded end-portions. When the cross-head is retracted, the spring 17 retracts the member 16, thus collapsing or sheathing the thread-equipped ends of the levers, so that the threads will clear the threads in the mouth of the container. The mandrel is equipped with a rigidly-secured collar 21 disposed a short distance back of the cross-head 7, so that after the mandrel is collapsed it will be withdrawn by the cross-head 7 engaging the collar 21. The range of movement of the pistons is sufficient to effect the complete withdrawal of the mandrel from the mold; or, at least, it should be sufficient to cause the mandrel to clear the mouth of the carboy, so as to permit removal of the carboy from the mold.

The lever-actuating member 16 is equipped with lugs 16^a provided with inclined or divergent cam-slots 16^b. The cam-slots 16^b are engaged by cam-studs 22, with which the rear ends of the levers 14 are equipped. Thus, it will be understood readily that when the member 16 slides forwardly with relation to the mandrel the front ends of the levers will be separated; and when the member 16 is retracted by the spring 17, during the recession of the cross-head 7, the front ends of the levers 14 will be forced toward each other, or collapsed.

The mandrel tip is provided, in front of the enlarged portion 12^a, with a shoulder 23 affording a wall for the front edge, or lip, of the bottle-mouth; and the levers are correspondingly shouldered to continue this wall across the recesses in which the levers are located.

The mechanism D for forcing the molten metal, that is, the hot plastic glass, into the mold, comprises: a plunger 24 on the lower end of a piston-rod 24^a, whose upper end is

equipped with a piston 24^b; a pressure cylinder 25 adapted to receive air or fluid under pressure for actuating the piston in both directions; a pressure pipe 26 adapted to deliver fluid under pressure to the cylinder; 70 a valve 27 controlling the admission to and exhaust from the cylinder. The valve 27 is equipped with an actuating-handle 28 which is located within convenient reach of an operator standing in position to operate the foot-lever 6^c. The cylinder 25 is provided with ports 18^a which serve alternately as admission and exhaust ports for admitting pressure to either end of the cylinder and permitting exhaust from the other 80 end. The plug-valve 27 is provided with suitable ports to regulate the admission and exhaust.

The carriage D', which is movable forwardly and rearwardly, that is, longitudinally with respect to the mandrel C, comprises a pair of slides 29, mounted on horizontal guide-bars 30 fixedly secured to supporting brackets 31 rigidly mounted on the bed-plate A; standards 32 fitted in the tubular sockets 29^a which are formed integrally with the tubular slides 29; and fittings 33 fixedly secured on the upper ends of the standards 32 and serving to support the cylinder 25, which is firmly connected to the fittings 33, as by means of screws, or bolts, 34. It thus appears that the carriage may be shifted rearwardly to carry the cylinder 25 to the dotted position shown in Fig. 1, thus bodily shifting the mechanism D so as to uncover the mold B. The locking cams D^a comprise arms carried by split clamping-rings 35 which are secured on the uprights 32 just above the fittings 29^a. The cams D^a are adapted to 105 make sliding contact with the lock-lugs 3^c of the upper mold-sections.

The mechanism D^a for shifting the carriage D' preferably comprises a transverse rock-shaft 36 journaled in brackets 37 secured to the rear end of the bed-plate A, said rock-shaft being equipped with a hand-lever 36^a, which, when the mechanism D is in operative position, inclines forwardly somewhat, as shown by the full lines in Fig. 115 1; a pair of short arms 38 rigidly secured to the rock-shaft; and a pair of links 39 connecting the arms 38 with the tubular slides 29. The hand-lever 36^a is disposed at the same side of the machine as the foot-lever 6^c, within convenient reach of an operator standing in position to actuate the foot-lever.

The mandrel-cooling device E preferably comprises a hollow annular ring 40, with 125 which communicates an air-pressure supply pipe 40^a which extends through and is secured to the bed-plate A. The hollow annulus 40 occupies a vertical plane a short distance back of the mold, and the mandrel 130

extends therethrough. When the mandrel is withdrawn, it will be cooled by air currents directed upon it from the annulus 40, which has its inner wall provided with 5 a series of perforations 40^b.

Compressed air is supplied to the cylinders 8 of the mechanism C' through a flexible pipe, or hose, 9^b.

As already mentioned, the plunger 24 is 10 of rectangular cross-section and works snugly in the vertical passage of the mold which serves as a charging cavity for the hot plastic glass. The lower end wall of the plunger conforms to the outer surface 15 of the mouth-portion of the carboy, being concave and slightly sloping, as will be understood from Figs. 7 and 10, that is, the lower end wall of the plunger conforms to a segment of a truncated cone, and serves 20 to complete the circumferential wall of the mold-cavity, when the plunger is in completely depressed position. Thus, the plunger itself serves as a section of the mold.

In accordance with the improved method 25 of carboy manufacture contemplated by this invention, the vertical channel of the mold in which the plunger 24 works is of sufficient capacity to hold the necessary amount of plastic glass to form the mouth-portion 30 of the bottle, or slightly more than the necessary amount; and the glass is allowed to flow from a collecting rod, or puddling rod, into the cavity until it is approximately filled, and is then snipped off by the operator, who, 35 after shifting the mechanism D to the full line position shown in Fig. 1, then operates the valve 27 through the medium of the lever 28 to admit pressure to the upper end of the cylinder 25, thereby causing the piston to 40 descend, so that the plunger 24 will force the glass into the annular space about the mandrel, it being assumed, of course, that the neck of the carboy has already been entered in the mold by an assistant. As the glass 45 flows into the mold-cavity, it flows over and about the end-portion of the neck of the carboy and becomes thoroughly welded thereto and virtually integral therewith. The piston 24 continues its downward descent until 50 the lower end of the piston occupies the annular plane of the circumferential wall of the mold-cavity, the plastic glass being wholly expelled from the channel in which the plunger 24 works. The operator soon 55 acquires the faculty of measuring, with the eye, approximately the correct amount of glass required for forming the mouth-portion of the bottle; and he designedly uses a slight excess of glass, so that as the plunger 60 24 comes to the lower end of its traverse, the pressure will force the carboy slightly away from the mold, it being understood that the die is so formed as to permit this action, and the assistant permits the carboy to recede 65 slightly under this pressure after the mold-

cavity has been filled to its capacity. In Fig. 7, the dotted line 41 indicates approximately the original end-portion of the neck of the carboy, that is, the end-portion of the neck before the glass which forms the reinforcement of the neck and mouth of the bottle has been forced into the mold. Preferably, the outer circumferential surface of the original neck-portion of the carboy for a distance of approximately $\frac{3}{4}$ of an inch from the extreme 70 end of the neck is cylindrical, or, if flaring, is only slightly so, the purpose being to facilitate the slight necessary movement of the carboy away from the mold, without leaving any gap through which plastic glass 75 might be expressed.

In practice, it is found that the improved method can be practised without any noticeable or objectionable variation in the length of the carboy-neck. The advantage of this 80 method of manufacture is that the mouth-portion of the carboy may be given a smooth exterior in the pressing operation, and there is no wastage of glass. Heretofore, it has been the practice to employ a charging cavity of larger diameter than the plunger 85 which serves to force the charge into the mold-cavity, so that a cup of glass forms about the plunger in the charging cavity. During the pressing operation, the bottom of 90 this cup of glass being connected by a rod of glass with the mouth-portion of the carboy; and it has been necessary, following such practice, to break this cup off, this practice involving a considerable wastage of 95 glass besides being otherwise objectionable.

It is believed that the operation will be fully understood from the description given. It may be added, however, that after the 100 pressing operation, the operator turns the handle 28 so as to admit pressure to the lower end of the cylinder 25 and exhaust the air from the upper end of said cylinder, so that the piston 24^b will raise the plunger 24 from the mold. As the plunger 24 nears the 105 upper end of its traverse, it lifts the locking cap D^a from the mold extensions 3^b. The operator then, through the medium of the lever 36^a, shifts the pressure mechanism D rearwardly as far as it will go, thus withdrawing the locking cams D^c from the mold. The operator then depresses the foot-lever 6^c, thus throwing the upper quarter-sections 110 of the mold open, so that the carboy can be removed. At the desired instant, the operator turns the handle 9^a so as to admit pressure to the front ends of the cylinders 8, and at the same time permit the rear ends of said 115 cylinders to exhaust, so that the cross-heads 7 will be retracted, thus causing the mandrel to be collapsed and then withdrawn from the mold. It is usually desirable to perform this operation before causing the plunger 24 to be withdrawn, and before the mold is unlocked. During the interval when the car- 120

boy is being removed and replaced by a fresh carboy, the air delivered by the cooling device E plays on the mandrel, so that it will not become excessively hot when subjected to repeated operations. Usually, also, the operative end of the mandrel is lubricated between operations.

In preparing the machine for the reception of a fresh carboy, the operator usually projects the mandrel into the mold before closing the mold and shifting the pressure mechanism D to an operative position.

The present invention constitutes, in some respects, an improvement on the invention set forth and claimed in my pending application No. 265,040, filed December 2, 1918.

The foregoing detailed description has been given for clearness of understanding only, and no unnecessary limitation should be understood therefrom, but the appended claims should be construed as broadly as permissible in view of the prior art.

What I regard as new, and desire to secure by Letters Patent, is:

25 1. In a machine for the purpose set forth, the combination of a mold provided with an opening for receiving the neck of a container and an opposed opening for receiving a mandrel, said mold being provided at one side of the mold-cavity with a charge-receiving cavity, a mandrel normally projecting into the mold-cavity, and pressure mechanism provided with a plunger working snugly through said charge-receiving cavity and having an end-portion adapted to substantially register with and serve as a section of the wall of the mold-cavity at the end of the pressing operation.

2. In a machine for the purpose set forth, the combination of a mold comprising longitudinally separable sections adapted to receive between them the neck of a container, said mold being provided at one side of the mold-cavity with a passage for a plunger, pressure mechanism having a plunger working through said passage and having its inner end-portion adapted to substantially register with and serve as a portion of the wall of the mold-cavity, a mandrel normally extending into the mold-cavity, and means for projecting and withdrawing said mandrel.

3. In a machine for the purpose set forth, the combination of a fixed lower mold-section, a pair of complementary upper mold sections provided with complementary upward extensions affording between them a plunger passage, said upper sections being mounted to swing on horizontal pivots, a plunger working through said plunger passage and adapted to force plastic glass into the mold-cavity, said mold having at its forward side an opening for receiving the neck of a container, and having at its rear side an opening for the reception of a mandrel, a

mandrel projecting into the mold-cavity and equipped with sheathable sections provided with thread-segments, and means for projecting and sheathing the segments of the mandrel and for projecting and retracting the mandrel.

4. In a machine for the purpose set forth, the combination of a mold comprising longitudinally separable sections adapted to receive between them the neck of a container, 75 said mold being provided at one side of the mold-cavity with a plunger passage, pressure mechanism provided with a plunger working in said passage, a mandrel extending into the mold-cavity and equipped 80 with collapsible thread-forming means and a pressure-actuated piston device adapted to project and retract said mandrel.

5. In a machine for the purpose set forth, the combination of a mold comprising longitudinally separable sections adapted to receive between them the neck of a container and an opposed mandrel, said mold being provided at one side of the mold-cavity with a charge-receiving cavity, a mandrel 90 extending into the mold-cavity and equipped with expansible thread-forming means, a 95 85 90 95 100 105 110 and adapted to be projected into the mold-cavity, a stop limiting the movement of projection of the mandrel, a pair of levers mounted on the mandrel and provided with 5 thread-forming segments, a lever-actuating member slidably mounted on the mandrel, spring-connections between said lever-actuating member and said mandrel, a piston-actuated cross-head adapted to project the 10 mandrel through the medium of said lever-actuating mechanism and spring until said stop is engaged and then to actuate said levers, a shoulder on the mandrel adapted to be engaged by said cross-head and there- 15 by cause retraction of the mandrel during the return stroke of said cross-head, and shiftably mounted pressure mechanism provided with a plunger adapted to force plastic material from the charge-receiving cavity 20 into the mold-cavity.

8. In a machine for the purpose set forth, the combination of a mold comprising longitudinally separable sections adapted to receive between them the neck of a container 25 and an opposed mandrel, said mold being provided at one side of the mold-cavity with a charge-receiving cavity, a mandrel-guide, a mandrel longitudinally movable therein and equipped with a stop adapted to limit 30 projection of the mandrel, and mandrel having a tip-portion adapted to extend into the container-mouth within the mold, said tip-portion having an enlarged base and being provided with slots, a pair of levers pivotally mounted in said slots and equipped at 35 their front ends with thread-segment forming means, a lever-actuating member slidably mounted on said mandrel, spring connection between said lever-actuating member and said mandrel, a stop on said mandrel a short distance in the rear of said lever-actuating member, a cross-head interposed between said lever-actuating member, and the adjacent stop, said mandrel extending 40 freely through said cross-head, a pressure-actuating piston device carrying said cross-head, and shiftably mounted pressure mechanism provided with a plunger adapted to force plastic material from the charge- 45 receiving cavity into the mold-cavity.

9. In a machine for the purpose set forth, a mandrel-guide, a tubular mandrel longitudinally movable in said guide and equipped with a tip-portion adapted to project into a mold, expansible thread-forming segments mounted in recesses in the tip-portion of the mandrel, an actuating member for said segments slidably mounted on the mandrel, a tension spring within the mandrel having its front end connected with 55 said segment-actuating member and having its rear end connected with the mandrel, a reciprocal member adapted to project the mandrel through the medium of said segment-actuating member and spring, and a 60

stop on the mandrel adapted to be engaged by said last-named member to effect withdrawal of the mandrel.

10. In a machine for the purpose set forth, the combination of a piston-actuating cross-head, a mandrel extending through said cross-head, a guide for said mandrel, a stop on said mandrel adapted to limit the movement of projection of the mandrel, expansible thread-forming segments mounted on the 70 mandrel, an actuating member for said thread-forming segments mounted on the mandrel and adapted to be engaged by said cross-head, spring connections between said last-named member and said mandrel, whereby the mandrel may be projected through the medium of said last-named member, and a stop on the mandrel adapted to be engaged by said cross-head to effect withdrawal of the mandrel after the collapsing 75 of the thread-forming segments.

11. In a machine for the purpose set forth, the combination of a mold comprising longitudinally separable sections adapted to receive between them the neck of a container 90 and an opposed mandrel, said mold being provided at one side of the mold-cavity with a charge-receiving cavity of rectangular cross-section, pressure mechanism provided with a plunger of rectangular cross-section 95 working snugly through said charge receiving cavity and having a lower end adapted to serve as a section of the wall of the mold-cavity when the plunger is in depressed position, a mandrel, and means for projecting 100 the mandrel into the mold and withdrawing it therefrom.

12. In a machine for the purpose set forth, the combination of a mold comprising longitudinally separable sections adapted to receive between them the neck of a container 105 and an opposed mandrel, said mold being provided at one side of the mold-cavity with a charge-receiving cavity of rectangular cross-section, pressure mechanism provided with a plunger of rectangular cross-section working snugly through said charge-receiving cavity and having an inclined concave lower end wall adapted to serve as a 110 section of the wall of the mold-cavity when the plunger is in depressed position, a mandrel, and means for projecting the mandrel into the mold and withdrawing it therefrom.

13. In a machine of the character set forth, the combination of a bed-plate, a lower 120 mold-section fixedly mounted thereon and a pair of complementary upper mold-sections provided with complementary upward extensions affording a charge-receiving cavity, said upper mold-sections being pivotally 125 mounted to permit them to be swung to open position, a mandrel disposed above the bed-plate and having an operative end equipped with thread-forming means, means for effecting projection and withdrawal 130

of the mandrel, bodily shiftable pressure mechanism disposed above the mold and equipped with a plunger adapted to force a charge from the charge-receiving cavity 5 into the mold-cavity, mold-locking means shiftable with said pressure mechanism and adapted to maintain the mold in locked condition while the pressure mechanism is in the retracted position permitting introduction of plastic material into the charge-receiving cavity, and a mold-locking member mounted on said plunger and withdrawable thereby when the plunger is lifted.

14. The method of providing the neck of a carboy with a reinforcing head and mouth-portion, which comprises: introducing the carboy-neck and a withdrawable mandrel through opposed openings in a mold which is provided with a mold-cavity and at one 20 side of said mold-cavity with a plunger- 25 passage, introducing plastic material into said plunger-passage and completely expressing said material from the plunger-passage into the mold-cavity by means of a plunger which works snugly in the plunger-passage and has a lower end which affords a section of the wall of the mold-cavity, the carboy-neck being allowed to recede from the mold sufficiently to compensate for any 30 excess of material introduced into the charge-receiving cavity.

15. The method of providing the neck of

a carboy with a reinforcing head and mouth-portion, which comprises: introducing the carboy-neck and an opposed withdrawable 35 mandrel into a sectional mold which is provided with a mold-cavity and a plunger- 40 passage opening into one side of the mold-cavity; introducing into the plunger-passage a charge of plastic material slightly in excess of the amount which will be accommodated by the mold-cavity; and completely 45 forcing the charge of material from the charge-receiving cavity into the mold-cavity by means of a plunger whose inner end conforms to and affords a section of the wall of the mold-cavity.

16. In a machine for the purpose set forth, the combination of a mold comprising longitudinally separable sections adapted to receive between them the neck of a container and an opposed mandrel, said mold being provided at one side of the mold-cavity with a charge-receiving cavity, pressure mechanism provided with a plunger conforming 55 to and working snugly through said charge-receiving cavity and having a lower end adapted to register with and serve as a section of the wall of the mold-cavity when the plunger is in depressed position, a mandrel, and means for projecting the mandrel into the mold and withdrawing it therefrom.

HARRY M. BROWN.
